Erospha, Inc., Brooklyn, N. Y., a corporation of
New York

Application February 13, 1933, Serial No. 656,641

18 Claims. (Cl. 103—133)

This invention relates to fluid actuating devices and particularly relates to pumps for liquids and gases and to compressors for gases and vapors and other similar apparatus.

5 Although the present invention will be particularly described in connection with liquid pumps it is also to be understood that it may be employed with spherical engines or other apparatus where fluid or liquid is passed into the casing to cause a shaft or mechanism to be actuated, the flow of liquid or fluid being the source of energy.

10 It is an object of the present invention to provide a spherical engine and particularly a durable pump which may be operated directly from a rotating shaft to give a continuous feed and/or to exert a continuous suction, which will be compact, light in weight and relatively inexpensive and which will have very few parts and not require costly lubricating installations or be readily subject to readjustments.

15 Among the other objects of the present invention are to provide a fluid actuator or a pump, which, although it is directly driven from a rotating shaft, has a very high mechanical efficiency and will have a metering action; which may be driven over a wide range of rotational speeds; which will be devoid of valves; which may be readily reversed; and which will produce both a substantially continuous suction at its inlet and a substantially continuous pressure at its outlet, all without the use of complicated or auxiliary mechanical apparatus, such as air bells, resilient diaphragm devices, and so forth.

20 Other objects will be sufficiently obvious and will appear during the course of the following specification.

25 In accomplishing the objects above stated the applicant has devised an altogether novel type of pump consisting of a casing, the interior chamber of which may take the form of a spherical section or segment with a peripheral spherical surface and flat or conical side walls; an oscillating impeller disc, the oscillating movement of which takes place both horizontally and vertically within said casing about a fixed center; a drive shaft which has an eccentric driving bearing for the impeller disc causing said impeller to undergo said movement within the casing resulting in substantially continuous movement of fluid from the inlet to the outlet; and a guide member mounted in said casing and received in a slot or socket in one edge of the impeller disc preventing the impeller disc from rotating while permitting relative

30 impeller will partake of said oscillating movement both laterally and vertically.

35 The impeller disc, the sides of which may be flat or outwardly converging or diverging, closely conforms to the spherical interior surface of the interior chamber along its entire periphery and converges toward the side walls of the chamber forming sealing surfaces or spaces, diametrically oppositely disposed on said walls thereof. As a result the interior chamber will be divided into two compartments which will be separated from each other by the impeller. The oscillating movement of the disc will continuously rotate these compartments within the casing.

40 The guide member is positioned between the inlet and outlet ports of the pump and constructed or associated with other elements, so as to prevent direct communication therebetween. As the compartments pass across the guide member, they will be divided thereby. During this passage they will decrease in volume on the approach or outlet side of the guide member, compressing and/or expelling fluid through the outlet port; and at the same time they will increase in volume on the removal or inlet side of the guide member, sucking fluid in through the inlet port.

45 When the pump as above described is to be made of large capacity, it has been found that the impeller disk often is of considerable weight and it is a further particular object of the present invention to provide an impeller disk for high capacity pumps which will have a relatively light weight and which will at the same time function efficiently to actuate the fluid or liquid in the desired fashion from the inlet to the outlet.

50 In accomplishing this last-mentioned object it has been found most convenient to provide an impeller disc with outwardly diverging liquid impelling surfaces. To reduce the weight only a relatively thin layer or wall of metal is left in the back of the impelling surface of the disc, and the interior of the impeller disc is hollow. When making the impeller disc of hollow construction, as described, it is necessary to provide means to prevent the fluid or liquid by-passing through the hollow spaces inside the hollow disc from the inlet to the outlet, and at all times the open space inside of the impeller disc must be prevented from communicating with either the inlet port or the outlet port.

55 The above and other objects will appear more clearly from the following detailed description, when taken in connection with the accompanying drawings, which illustrate several preferred embodiments of the inventive idea.

In the drawings:

Figs. 1 to 3 show one type of pump or one type of fluid actuating device constructed according to the present invention; Fig. 1 being a side sectional view; Fig. 2 being an axial sectional view upon the line 2—2 of Fig. 1; and Fig. 3 being a top sectional view upon the line 3—3 of Fig. 1;

Figs. 4 to 9 show the various constituent parts of the pump construction removed from the assembly; Fig. 4 being a perspective view of the impeller disc with the guide member in position; Fig. 5 being a perspective view of the impeller disc at a different angle; Fig. 6 being a side elevational view; Fig. 7 being a bottom view of the impeller disc; Fig. 8 being an exploded perspective view of the guide with its wing elements; and Fig. 9 being an axial elevation of the shaft;

Figs. 10 to 26 are diagrammatic views illustrating the operation of the pump or fluid actuating device of Figs. 1 to 3; and

Figs. 27 and 28 are side sectional views of two other impeller-shaft combinations.

The pump as shown in Figs. 1 to 3 of the drawings is provided with a casing C, a driving shaft 11, an impeller disc 21 and a guide member 25.

The casing C (Figs. 1 to 3) is formed of two half sections 7 and 8 provided with integral flanges 50 and with integral webs 52, the flanges 30 and webs on the opposite halves being connected together by the bolts 51. The casing sections 50 are also provided with a support plate 53, which is preferably integrally associated with the lower part of the casing C.

The inlet and outlet ports 9 and 10 communicate with the interior pump chamber I of the casing and they are formed half in each section 7 and 8 so that when these sections are bolted together the complete port will be formed.

The interior chamber I is provided with inwardly converging frusto-conical side walls 54 and a continuous peripheral spherical surface 55.

In the form of the invention shown (see Figs. 45 1 and 3 and also Figs. 14, 18, 22 and 26) the inlet port and the outlet port intersect the peripheral spherical surface 55 to form inlet and outlet ports 56 and 57. As indicated, both of the ports 9 and 10 decrease in flow area as 50 they approach the interior chamber I, the inlet port 9 decreasing at a more rapid rate than the outlet port 10 with the result that the area 56 of the inlet port at the peripheral surface 55 will be less than the area 57 of the outlet port 55 10.

The one side of the casing is provided with a boss 58 having a central opening into which is fitted the bearing sleeve 12. This bearing sleeve receives the shaft 11. Within the chamber I 60 casing C, the shaft 11 carries the ball element B. The lateral surfaces 19 and 17 of the ball B bear within the cavities 59 and 60 formed in the interior side walls 54 of the casing C. The ball element B is also provided with a thrust 65 bearing surface 16 which contacts with the flange 62 at the inner end of the bearing sleeve 12.

The ball element B is divided into two spherical conical sections 13 and 14 (see Figs. 2, 3 70 and 9) by a central slot 63 which is positioned obliquely to the axis of the shaft 11 and is provided with inwardly converging side bearing surfaces 18 and 20 and with the inside cylindrical bearing surface 15. The side bearing surfaces 75 18 and 20 are of truncated conical form and

converge toward the center point 82. The horizontal axis of the shaft 11 passes through this center point 82.

The impeller disc 21 is shown assembled with the pump in Figs. 1, 2 and 3 and is shown removed from the pump in Figs. 4, 5, 6 and 7. The impeller disc 21 is carried and caused to undergo an oscillating movement by the slot 63 of the shaft 11 (see Fig. 9).

The piston is formed of two outwardly diverging conical shaped plates or walls 22 and 23. These plates or walls 22 and 23 converge together toward the center point 82 and are joined together short of said center point by the annular peripheral wall 24. The inner converging 15 sides of the plates 22 and 23 adjacent to the conical surfaces 18 and 20 of the shaft 11 are depressed as indicated at 66 in Fig. 5. These depressed portions receive the bearing insert 65 which takes the shape of the side walls 22 and 20 23 of the impeller. The bearing insert 65 extends over the inside peripheral surface 24 which bears against the cylindrical oblique surface 15 of the shaft (Fig. 9).

When the impeller is oscillated due to the eccentric movement of the slot 63 upon rotation of the shaft 11, it is prevented from rotating by the guide member 25 which slides in the transverse slot 27 extending across the bottom portion of the impeller disc 21 (see Figs. 1, 2, 4, 5, 30 6 and 7).

The guide 25 (see Figs. 1, 2, 4 and 8) consists of a truncated cone 68 provided with a central cylindrical opening 69 into which projects the pivot stud 26. The stud 26 is received in a central opening 70 in the casing C and is held against rotation by the key 71.

The inner surface 73 of the conical roller and the outer surface 74 are both spherical. The outer surface 74 contacts closely with the peripheral surface 55 of the chamber I while the inner spherical surface 73 of the guide member 25 rides upon the bottom spherical surface 25' of the slot 27 in the impeller 21. The side surfaces of the conical roller 68 will roll and slide 40 along the side surfaces 68' of the impeller slot 27. As indicated in Fig. 4, during the extreme positions in the oscillation of the impeller disc 21, the guide 25 and its roller 68 will slide partly out of the slot 27. In this position the inner spherical surfaces 73 of the roller 68 will ride over the spherical surfaces 16 and 19 of the ball element B of the shaft 11.

As indicated in Figures 1, 2, 5, 6 and 7 the sides and bottom of the slot 27 in the edge of the impeller 21 will be formed by a wall or plate 100, preferably of the same thickness as the side walls 22 and 23.

To prevent communication between the inlet and outlet ports directly across the bottom of the casing I past the slot 27, the fixed wings or plates 32 and 33 are provided (see Figs. 2, 3 and 8). These wings 32 and 33 extend from the side of the roller 68 of the guide 25 to the conical side walls 54 of the casing.

The inside adjacent faces 101 and 102 are shaped conically so as to contact closely and in a liquid-tight fashion with the sides of the roller 68 while the outside edge faces 103 and 104 are also conically surfaced so as to contact with the conical side walls 54 of the chamber I (see particularly Fig. 8). The inside edge faces 105 and 106 of the plates 32 and 33 are of spherical shape so as to contact closely with the bottom 25' of the slot 27 in the impeller disc 21 75

and/or with the spherical surfaces 17 and 19 of the ball element B.

The wing or plate 32 is provided with an extension 108 which fits into a slot 109 in the lower portion of the casing (see Figs. 2 and 8) while the wing 33 is provided with an integral stud 34 which is received in the cylindrical opening 109 in the lower side of the casing C and held against rotation by the key 110.

10 The metal wall 100 forming the bottom and sides of the slot 27 in the impeller disc 21 is provided with the laterally extending wings 28 and 29 which are of such size as to always cover the inlet and outlet port openings 56 and 57 (see particularly Figs. 14, 18, 22 and 26) and prevent flow of liquid from the inlet port to the outlet port in the space between the side walls 22 and 23 of the impeller. The outside surfaces of the wings 28 and 29, and also the edges 85 and 86 of the plates 22 and 23, are spherical so as to contact closely with the peripheral spherical surface 55 of the interior chamber I (see Figs. 1 to 3).

As indicated in Figs. 1, 3, 5 and 6, the impeller 21 is formed of two half sections, an upper section 150 and a lower section 151 carrying a slot 27, which half sections are provided with the contacting webs 30 which are bolted together at 31.

The operation of the pump is most conveniently shown from the diagrammatic views, Figs. 10 to 26. Fig. 10 diagrammatically illustrates the turning of the impeller disk 21, and Figs. 11 to 26 show side, front, top and bottom views of the impeller disk 21 and the guide member 25 in each of the positions I, II, III and IV, designated.

Figs. 11, 12, 13, and 14 are, respectively, side, front, top and bottom views of the impeller 21 and guide member 25 in position I; Figs. 15, 16, 17 and 18 are corresponding views in position II; Figs. 19, 20, 21 and 22 are corresponding views in position III; and Figs. 23, 24, 25 and 26 are corresponding views in position IV.

When the shaft 11 rotates, the impeller 21 will be caused to sweep backwardly and forwardly both horizontally and vertically in the interior chamber I with the result that said impeller will partake of an oscillation.

At the same time the axes about which the impeller tends to swing will also tend to rotate about the fixed common center point 82 of the casing, impeller and the shaft. The horizontal axis of the impeller will swing in a horizontal plane and the vertical axis will swing in a vertical plane. This last-mentioned vertical plane will also tend to rotate or oscillate about the central vertical axis of the casing as indicated in Figs. 14, 18, 22 and 26.

As a result of this movement all points on the periphery of the impeller 21 removed from the horizontal axis will tend to move along lemniscate curves which become of greater latitude as the point becomes elevated or depressed and removed from the center point 82 so that points at the top and bottom of the impeller 21 will move in lemniscate curves of maximum amplitude. These curves will lay a spherical surface described upon a radius equal to the distance of the point from the center point 82. Because of this movement no substantial acceleration or deceleration forces will be exerted upon the mass of the impeller disk, with the result that the abrupt changes in acceleration characteristics of the reciprocating piston pump are altogether eliminated.

75 As indicated in Figs. 11, 12, 13 and 14, respec-

tively, in side, front, top and bottom views, the impeller 21 will divide the interior I of the casing C into two compartments 92 and 93 which are symmetrically disposed in respect to the center point 82 of the pump. In Figs. 11, 15, 19 and 23 the compartment 92 is to the right of the impeller, while the compartment 93 is to the left of the impeller. In Figs. 12, 16, 20, 24, the compartment 92 is in front of the impeller while the compartment 93 is to the rear of the impeller. 10 In Figs. 13, 17, 21 and 25, the compartment 92 is to the right of the impeller, while the compartment 93 is to the left of the impeller. In Figs. 14, 18, 22 and 26 the compartment 93 is to the left of the impeller, while the compartment 15 92 is to the right of the impeller.

It is apparent that these compartments, due to the oscillation movement of the impeller 21, are caused to rotate within the interior chamber I of the casing C.

During rotation, these compartments 92 and 93 are successively opened and closed to the inlet 56 and then to the outlet 57 so that fluid or liquid which is received through the inlet 56 will be carried to the outlet 57. These compartments 25 92 and 93 will transfer liquid or fluid through the upper half of the casing from the inlet 56 to the outlet 57. Transfer of fluid or liquid reversely from the outlet to the inlet in the lower half of the chamber I is prevented by the guide 25 and 30 its wings 32 and 33.

It will be noted in Figs. 14, 18, 22 and 26, that the chambers 92 and 93 must move through the guide, with the guide 25 and wings 32 and 33 preventing communication from one side of the 35 chamber to the other as it is moving through said guide.

As shown in Fig. 14 the compartment 93 is moving downwardly and is bisected by the wing 32, while in Fig. 18 both compartments are divided by the wings 32 and 33. In Fig. 22 only the compartment 92 is divided by the wing 33 and as the compartment continues to move downwardly the greater part of its volume also moves below the wing 33 with a corresponding decrease 45 of volume above the wing 33.

As the compartments 92 and 93 move through the wings 32 and 33 therefore, the volume of the subdivision on the outlet side 57 of the guide 25 decreases with the result that the liquid or fluid 50 is then forced or squeezed out through said outlet 57. At the same time the volume of the compartment on the inlet side of the guide 25 increases with the result that the liquid is sucked in through the inlet 56 to fill the increasing volume 55 on that side. It will thus be apparent that each compartment 92 and 93 has inlet and outlet portions or subdivisions of progressively changing volume, the volume successively increasing in communication with the inlet 11, being cut off 60 from the inlet after it has been filled, then achieving communication with the outlet 57 and decreasing in volume while in communication with the outlet until all of the liquid or fluid has then been forced out through said outlet. 65

The inlet and outlet subdivision of each compartment 92 and 93 in addition to being separated by the wings 32 and 33 are also separated by the convergence between the side of the impeller 21 and the side of the chamber I. This area or line 70 of convergence is indicated for the compartment 92 in Figs. 12, 16, 20 and 24 by the dotted line 94 and it will be noted that it rotates within the interior I in the same direction as the shaft. This area or line of convergence is also indicated at 75

in Figs. 11, 17, 18, 19, 25 and 26. The corresponding line or area of convergence for the compartment 93 is indicated at 95 in Figs. 11, 17, 18, 19, 25 and 26. It will be noted that the area or line 5 95 is always symmetrically disposed diametrically opposite to the area or line 94 in respect to the center point 82.

In Figs. 11, 12, 13 and 14, the compartment 92 has just been filled and is being cut off from the 10 inlet 56 by spherical plate element 28 of the impeller, and is just about to be opened to the outlet 57 by the spherical plate element 29. The spherical plate elements 28 and 29 together with the contact areas 94 and 95 function as inlet and 15 outlet valves since they serve to open and cut off from the inlet 56 and to open and cut off the outlet 57 to the compartments 92 and 93.

In the position shown in Figs. 11 to 14, the 20 line of contact 94 coincides with the contact of the wing 33 with the side wall 54 of the interior I so that the compartment 92 in this position is not divided nor is it decreased in volume by the 25 volume of the wing. To reach this position the compartment 92 has been increased in volume while in communication with the inlet 56 on the inlet side of the guide 25, with the result that an amount of fluid or liquid equal in amount to the maximum volume of the compartment 92 has been sucked or drawn thereto.

30 Then as the shaft 11 continues to move from the position I of Figs. 11 to 14, to the position II of Figs. 15 to 18, the inlet valve plate 28 of the impeller 21 will reverse its movement and start to swing to the right as indicated in Fig. 18, while 35 the outlet valve plate 29 will sweep across the outlet port 57 from the position of Fig. 14 to the position of Fig. 18, opening the outlet port 57 to the compartment 92. As this is occurring, the compartment 92 is being moved through the wing 33 so that as it is opening to the inlet 56, liquid or 40 fluid being sucked into the opening portion on the inlet side up to the line 94 (see Fig. 16), while due to the decreasing volume of the portion of the compartment 92 on the outlet side of the wing 33 a corresponding amount of liquid and fluid is being 45 forced outwardly through said outlet 57.

In the position of Figs. 19 to 22, the compartment 92 is being bisected by the wing 33 and it is 50 open one-half to the inlet 56 and one-half to the outlet 57 with the volume in communication with the inlet increasing while the volume with the outlet is decreasing.

When the pump as above described is to be made of large capacity, it has been found that the impeller disc often is of considerable weight and it is a further particular object of the present invention to provide an impeller disc for high capacity pumps which will have a relatively light weight and which will at the same time function efficiently to actuate the fluid or liquid in the desired fashion from the inlet to the outlet.

60 In Figs. 23 to 26 the area has reached the position 94 in Fig. 24. The major portion of the volume of compartment 92 has been opened in respect to the inlet 56 and with the last portions of liquid contained in said compartment on the outlet side being forced out through said outlet 57.

The valve plate 29 (see Fig. 26) is swinging to 70 the right to cut off the outlet port 57. The valve plate 29 is swinging over to cut off inlet port 56 after the compartment 92 has been filled and the contact area 94 has passed the wing 33. The compartment 92 is first closed and then opened 75 to the outlet and inlet ports 56 and 57 by the

plates 28 and 29, as the area 94 sweeps across said ports.

The operation of the other compartment 93 is obvious from what has been described in connection with compartment 92.

It is therefore evident that as the shaft 11 rotates and the impeller 21 oscillates, liquid or fluid will be continuously acted upon and moved from the inlet 56 to the outlet 57 by the compartments 92 and 93. It will be noted that the pump is substantially volumetric in action except for a very 10 small amount of leakage across the peripheries 85 and 86 and across the lines of areas 94 and 95, the combined volume of the chambers 92 and 93 being transferred from the inlet to the outlet once 15 for each complete revolution of the shaft.

The converging of the intake port 9 and the diverging of the outlet port 10 are regulated so that the liquid or fluid will flow into and from the pumping compartments 92 and 93 through the 20 openings 56 and 57 with a minimum of turbulence. In order to enable the fluid or liquid to pass into and out of the casing at a constant velocity without excessive turbulence the cross 25 sectional area of the inlet and outlet ports 56 and 57 opened for the entry or exit of fluid or liquid must be equal to or greater than the maximum transverse area of the pumping compartments 152 and 153 which is indicated at 36 in Fig. 2.

The modification illustrated in Fig. 27 30 comprises an annular piston 37, the impeller portion of which consists of a circular V-shaped section formed by converging walls 38 and 39. This V-shaped section is carried by ball bearings 40. The spherical support for the piston consists of 35 two halves 41 and 42 which are connected together by a key member 43. The member 41 is an integral part of the shaft end 44, while the member 42 is integral with the shaft end 45.

The modification illustrated in Fig. 28 is similar to that shown in Fig. 27 and differs from the latter merely in the substitution of the roller bearings 46 for the ball bearings 40 shown in Fig. 27.

In considering the operation of the fluid actuating device of the present invention, which operation has been diagrammatically illustrated and described in connection with Figs. 10 to 26, it is to be noted that the impeller 21 in the course of its oscillating movement causes a displacement 50 of fluid both when it moves toward the wall of the casing C and when it moves away from the wall of the casing C. In the former case the fluid is forced out of the casing through the outlet or is forced from one part of the interior chamber 55 of the casing to another part of the interior chamber of the casing.

Since the entire side wall or side surface of the impeller does not move toward the side wall of the interior chamber simultaneously but rather 60 is caused to move over said surface so that one portion of the side of the impeller is advancing toward the side of the casing, while another portion of the side of the impeller may be moving away from the same side wall of the impeller, 65 it is evident that the oscillating movement of the impeller will result in moving fluid circularly around within the interior of the casing.

It is thus evident that the displacement action of the rolling oscillating impeller of the present 70 invention differs substantially from the displacement action of the piston of a reciprocating pump in that whereas the motion of the reciprocating piston causes a linear movement of fluid to the end of a cylinder, in the device of the present 75

application on the other hand, the displacement action of the impeller causes a rotational movement of the fluid from the inlet to the outlet along the face of the impeller. The guide with its adjuncts extending between the side walls of the chamber I causes the oscillating action to draw in fluid from the inlet and to force fluid out through the outlet.

The volume for containing fluid or liquid within the casing of the device will always be substantially constant since it will be equivalent to the volume of the interior chamber minus the volume of the impeller and the volume of the guide with its adjuncts. As previously described, the impeller will divide the chamber into two wedge-like compartments which, although they are of substantially constant volume throughout operation of the device (except for the volume of the guide or its adjuncts which may project into them) they nevertheless will have portions of varying volumetric capacity in communication with the inlet and outlet, the volume in communication with the inlet increasing while the volume in communication with the outlet is decreasing.

From this point of view it may be considered that the guide is a fixed fluid-impelling device which moves relatively through the compartments on opposite sides of the impeller to increase their volume on one side, causing drawing in of liquid from the inlet and to decrease their volume on the other side, causing discharge of liquid through the outlet. This action, however, is quite different from the action of a reciprocating piston pump in which there is a fixed piston and a movable cylinder, in that in the present invention the displacement member or the guide member moves continuously through the compartments, one after the other without the abrupt reversals as occur in all reciprocating pumps.

It is apparent from the foregoing description of the operation, that the shaft may be rotated in either direction, and that as a result of each reverse rotation the inlets and outlets will be similarly reversed. The discharge output of the device is proportional to the speed of rotation of the shaft, while the head or height of delivery is independent of the speed of rotation.

The present application is a continuation in part of my copending application Serial No. 636,502, filed Oct. 5, 1932.

The matter shown and described in the present application but not claimed herein is covered in my copending applications Serial Nos. 656,637; 656,638; 656,639; 656,640; filed respectively Feb. 13, 1933; 673,244 and 673,245, filed May 27, 1933 and 696,944, filed Nov. 7, 1933. The guide and separating wall arrangement of the present application, as well as the impeller construction, may be utilized in the spherical machines of said copending applications. The guide may be used with other shapes of impeller, for example as the converging impeller shown in application #656,637, in a gas or vapor compressor such as shown in #656,638, with an internal lubrication system such as shown in #656,640, and in a vacuum pump such as shown in #656,642. The novel features of the present invention may also be utilized in connection with the separated guide and separating wall, as disclosed in #673,244 and #673,245, and also in connection with the peripheral and side surface or space packing or sealing disclosed in #696,944, which last-mentioned application also discloses rotating side walls.

What is claimed is:

1. In a fluid actuating device, a casing having a spherical interior chamber with inlet and outlet ports, an impeller therein dividing said chamber into a plurality of separated compartments, a drive shaft with an eccentric cam portion for causing said impeller to oscillate within the chamber, and a guide member connected to said impeller and to said casing for preventing rotation of said impeller while permitting it to oscillate whereby said compartments will rotate and transfer of fluid from said inlet to said outlet will result, said impeller being of hollow form and comprising outwardly diverging walls, said interior chamber being provided with conical sides and the exterior sides of said impeller moving circularly past the conical sides of said chamber, said impeller being provided with interior closure means extending between said side walls, said closure means extending to the periphery of said side walls of said impeller, whereby the impelling action of said impeller is restricted to the exterior sides of said impeller.

2. In a fluid actuating device, a casing having a spherical interior chamber with inlet and outlet ports, an impeller therein dividing said chamber into a plurality of separated compartments, a drive shaft with an eccentric cam portion for causing said impeller to oscillate within the chamber, and a guide member connected to said impeller and to said casing for preventing rotation of said impeller while permitting it to oscillate whereby said compartments will rotate and transfer of fluid from said inlet to said outlet will result, said impeller being of hollow form and comprising inwardly converging walls having conical impelling surfaces the apexes of which meet at the center point of the impeller, said interior chamber being provided with conical sides and the exterior sides of said impeller moving circularly past the conical sides of said chamber, said impeller being provided with interior closure means extending between said side walls, said closure means extending to the periphery of said side walls of said impeller, whereby the impelling action of said impeller is restricted to the exterior sides of said impeller.

3. In a fluid actuating device, a casing having a spherical interior chamber with inlet and outlet ports, an impeller therein dividing said chamber into a plurality of separated compartments, a drive shaft with an eccentric cam portion for causing said impeller to oscillate within the chamber, and a guide member connected to said impeller and to said casing for preventing rotation of said impeller while permitting it to oscillate whereby said compartments will rotate and transfer of fluid from said inlet to said outlet will result, said impeller being of hollow form and having a slot and partial peripheral walls which project over said ports, said interior chamber being provided with conical sides and the exterior sides of said impeller moving circularly past the conical sides of said chamber, said impeller being so constructed as to prevent circulation of fluid through the hollow interior thereof, whereby the impelling action of said impeller is restricted to the exterior sides of said impeller.

4. In a fluid actuating device, a casing having a spherical interior chamber with inlet and outlet ports, an impeller therein dividing said chamber into a plurality of separated compartments, a drive shaft with an eccentric cam portion for causing said impeller to oscillate within the

- chamber, and a guide member connected to said impeller and to said casing for preventing rotation of said impeller while permitting it to oscillate whereby said compartments will rotate and transfer of fluid from said inlet to said outlet will result, said impeller being of hollow form and having outwardly diverging side walls, the maximum cross-sectional area of said compartments being about the same as the available area of said ports, said interior chamber being provided with conical sides and the exterior sides of said impeller moving circularly past the conical sides of said chamber, said impeller being provided with interior closure means extending between said side walls, said closure means extending to the periphery of said side walls of said impeller, whereby the impelling action of said impeller is restricted to the exterior sides of said impeller.
- 20 5. In a fluid actuating device, a casing having a spherical interior chamber with inlet and outlet ports, an impeller therein dividing said chamber into a plurality of separated compartments, a drive shaft with an eccentric cam portion for causing said impeller to oscillate within the chamber, and a guide member connected to said impeller and to said casing for preventing rotation of said impeller while permitting it to oscillate whereby said compartments will rotate and transfer of fluid from said inlet to said outlet will result, said cam portion being formed of an obliquely slotted ball, the sides of said slot being of conical contour, said ball consisting of separable conical sections and said impeller being of hollow construction and having inwardly converging walls, said interior chamber being provided with conical sides and the exterior sides of said impeller moving circularly past the conical sides of said chamber, said impeller being so constructed as to prevent circulation of fluid through the hollow interior thereof, whereby the impelling action of said impeller is restricted to the exterior sides of said impeller.
- 30 6. In a fluid actuating device, a casing having a spherical interior chamber with inlet and outlet ports, an impeller therein dividing said chamber into a plurality of separated compartments, a drive shaft with an eccentric cam portion for causing said impeller to oscillate within the chamber, and a guide member connected to said impeller and to said casing for preventing rotation of said impeller while permitting it to oscillate whereby said compartments will rotate and transfer of fluid from said inlet to said outlet will result, said shaft cam portion including a grooved spherical element consisting of separable sections and said impeller being of hollow construction and having inwardly converging walls, and anti-friction bearings interposed between said impeller and said cam portion, said interior chamber being provided with conical sides and the exterior sides of said impeller moving circularly past the conical sides of said chamber, said impeller being so constructed as to prevent circulation of fluid through the hollow interior thereof, whereby the impelling action of said impeller is restricted to the exterior sides of said impeller.
- 40 7. In a fluid-actuating device, a casing having an interior fluid receiving chamber with spaced sides and spherical peripheral surfaces, said chamber being provided with inlet and outlet ports, an impeller located within said chamber having a peripheral spherical outside surface located in close adjuxta position to the peripheral surface of the chamber and having fluid actuating side walls which oppositely approach and diverge from the sides of the chamber, so as to form semi-circular wedge-like fluid conveying compartments to be rotated from the inlet to the outlet ports, separating means in said casing transversely located between the inlet and outlet ports, said separating means preventing direct communication between the inlet and outlet ports, the movement of said impeller causing a movement of fluid from the inlet port into the outlet port through the chamber, said impeller being provided with a transverse opening to receive said
- 45 8. In a fluid-actuating device, a casing having a fluid actuating chamber with spaced sides and spherical peripheral surfaces, said chamber being provided with inlet and outlet ports, and being provided with a central shaft connection, an impeller member located obliquely across said chamber having diametrically opposite linear contacts and divergent portions so as to form a plurality of reversely congruent semi-circular wedge-like actuating compartments, the outside portion of said impeller having a spherical surface located in close adjuxta position to the spherical surface of the chamber, a transverse separating means between said inlet and outlet ports received in a slot in said impeller, said shaft carrying a central cam element cooperating with said impeller to hold it in relatively oblique position within said chamber and to cause its side walls and the sides of the chamber to move relatively over one another and the spherical outside surface of the impeller to oscillate relatively laterally across said spherical peripheral surface, said impeller having outwardly diverging separated side walls, said impeller being provided with transverse walls extending between said side walls to the peripheral surface of said impeller, said transverse walls being substantially removed from said slot.
- 50 9. In a spherical machine, a casing having an interior fluid receiving chamber with spaced sides and spherical peripheral surfaces, said chamber being provided with inlet and outlet ports, an impeller located within said chamber having a peripheral spherical outside surface located in close adjuxta position to the peripheral surface of the chamber and having fluid actuating side walls which oppositely approach and diverge from the sides of the chamber, so as to form semi-circular wedge-like fluid conveying compartments to be rotated from the inlet to the outlet ports, separating means in said casing transversely located between the inlet and outlet ports, said separating means preventing direct communication between the inlet and outlet ports, the movement of said impeller causing a movement of fluid from the inlet port into the outlet port through the chamber, said impeller being provided with a transverse opening to receive said

- means, and a central oblique cam element for cooperating with said impeller, holding it in relatively oblique position within said chamber and for causing the side walls of said impeller and the sides of the chamber to move over one another within said chamber and to cause the peripheral outside surface of the impeller to oscillate relatively laterally across said chamber, said impeller having outwardly diverging separated side walls, and being formed of two conical disc-like members having cylindrical hub portions and lateral flanges, which flanges are bolted together.
10. In a spherical machine, a casing having an interior fluid receiving chamber with spaced sides and spherical peripheral surfaces, said chamber being provided with inlet and outlet ports, an impeller located within said chamber having a peripheral spherical outside surface located in close adiuxtaposition to the peripheral surface of the chamber and having fluid actuating side walls which oppositely approach and diverge from the sides of the chamber, so as to form semi-circular wedge-like fluid conveying compartments to be rotated from the inlet to the outlet ports, separating means in said casing transversely located between the inlet and outlet ports, said separating means preventing direct communication between the inlet and outlet ports, the movement of said impeller causing a movement of fluid from the inlet port into the outlet port through the chamber, said impeller being provided with a transverse opening to receive said means, and a central oblique cam element for cooperating with said impeller, holding it in relatively oblique position within said chamber and for causing the side walls of said impeller and the sides of the chamber to move over one another within said chamber and to cause the peripheral outside surface of the impeller to oscillate relatively laterally across said chamber, said impeller having outwardly diverging separated side walls; the space between the periphery of said separated side walls being covered at said transverse opening and for a sufficient extent on each side of said transverse opening to cover both inlet and outlet ports throughout the oscillation of said impeller.
11. In a spherical machine, a casing having a fluid-receiving chamber with spaced sides and spherical peripheral surfaces, said chamber being provided with inlet and outlet ports, and being provided with a central shaft connection, an impeller member located obliquely across said chamber to form a plurality of reversely congruent semi-circular wedge-like actuating compartments, the outside portion of said impeller having spherical surfaces located in close adiuxtaposition to the spherical surface of the chamber, a transverse separating means between said inlet and outlet ports received in a slot in said impeller, said shaft carrying a central cam element cooperating with said impeller to hold it in relatively oblique position within said chamber and to cause its side walls and the sides of the chamber to move relatively over one another and the spherical outside surface of the impeller to oscillate relatively laterally across said spherical peripheral surface, said central cam element including a grooved spherical element consisting of separable sections, and anti-friction bearings interposed between said impeller and said cam portion, said impeller member being of hollow construction and the hollow interior of said impeller being so enclosed at the exterior of the impeller as to prevent communication between said ports and to prevent liquid communication between said ports and said hollow interior, and said compartments extending between the exterior surfaces of the impeller member and the spaced sides, the impelling action of said impeller being restricted to the exterior side walls of said impeller.
12. In a spherical machine, a casing having a fluid-receiving chamber with spaced sides and spherical peripheral surfaces, said chamber being provided with inlet and outlet ports, and being provided with a central shaft connection, an impeller member located obliquely across said chamber to form a plurality of reversely congruent semi-circular wedge-like actuating compartments, the outside portion of said impeller having a spherical surface located in close adiuxtaposition to the spherical surface of the chamber, a transverse separating means between said inlet and outlet ports received in a slot in said impeller, said shaft carrying a central cam element cooperating with said impeller to hold it in relatively oblique position within said chamber.
13. In a spherical machine, a casing having a fluid-receiving chamber with spaced sides and spherical peripheral surfaces, said chamber being provided with inlet and outlet ports, and being provided with a central shaft connection, an impeller member located obliquely across said chamber to form a plurality of reversely congruent semi-circular wedge-like actuating compartments, the outside portion of said impeller having a spherical surface located in close adiuxtaposition to the spherical surface of the chamber, a transverse separating means between said inlet and outlet ports received in a slot in said impeller, said shaft carrying a central cam element cooperating with said impeller to hold it in relatively oblique position within said chamber and to cause its side walls and the sides of the chamber to move relatively over one another and the spherical outside surface of the impeller to oscillate relatively laterally across said spherical peripheral surface, said central cam element including a grooved spherical element consisting of separable sections, and anti-friction bearings interposed between said impeller and said cam portion, said impeller member being of hollow construction and the hollow interior of said impeller being so enclosed at the exterior of the impeller as to prevent communication between said ports and to prevent liquid communication between said ports and said hollow interior, and said compartments extending between the exterior surfaces of the impeller member and the spaced sides, the impelling action of said impeller being restricted to the exterior side walls of said impeller.
14. In a spherical machine, a casing having a fluid-receiving chamber with spaced sides and spherical peripheral surfaces, said chamber being provided with inlet and outlet ports, and being provided with a central shaft connection, an impeller member located obliquely across said chamber to form a plurality of reversely congruent semi-circular wedge-like actuating compartments, the outside portion of said impeller having a spherical surface located in close adiuxtaposition to the spherical surface of the chamber, a transverse separating means between said inlet and outlet ports received in a slot in said impeller, said shaft carrying a central cam element cooperating with said impeller to hold it in relatively oblique position within said chamber.

and to cause its side walls and the sides of the chamber to move relatively over one another and the spherical outside surface of the impeller to oscillate relatively laterally across said spherical 5 peripheral surface, said central cam element consisting of two spherical elements, the axes of which are oblique to the axes of said shaft and the bases of which consist of spherical surfaces and are rigidly connected to said shafts, one of 10 said spherical elements being provided with a central socket and the other being provided with a central projection, which socket and projection telescope into each other, said central cam element being provided with means to hold said 15 elements together.

15. In a spherical machine, a casing having a fluid-receiving chamber with spaced sides and spherical peripheral surfaces, said chamber being provided with inlet and outlet ports, and being 20 provided with a central shaft connection, an impeller member located obliquely across said chamber to form a plurality of reversely congruent semi-circular wedge-like actuating compartments, the outside portion of said impeller having spherical surface located in close ad- 25 juxtaposition to the spherical surface of the chamber, a transverse separating means between said inlet and outlet ports received in a slot in said impeller, said shaft carrying a central cam element 30 cooperating with said impeller to hold it in relatively oblique position within said chamber and to cause its side walls and the sides of the chamber to move relatively over one another and the spherical outside surface of the impeller 35 to oscillate relatively laterally across said spherical peripheral surface, said central cam element consisting of separable sections, one of which is provided with a socket and the other of which is provided with a nipple fitting into said socket, 40 said nipple carrying anti-friction bearings interposed between said impeller and said cam portion.

16. In a spherical machine, a casing having a fluid-receiving chamber with spaced sides and spherical peripheral surfaces, said chamber being provided with inlet and outlet ports, and being provided with a central shaft connection, an impeller member located obliquely across said chamber to form a plurality of reversely congruent semi-circular wedge-like actuation compartments, the outside portion of said impeller having a spherical surface located in close ad- 45 juxtaposition to the spherical surface of the chamber, a transverse separating means between said inlet and outlet ports received in a slot in said impeller, said shaft carrying a central cam element 50 cooperating with said impeller to hold it in relatively oblique position within said chamber and to cause its side walls and the sides of the chamber to move relatively over one another and the spherical outside surface of the impeller to oscillate relatively laterally across 55 said spherical peripheral surface, said central

cam element including a grooved spherical element consisting of two separable spherical sections, the inside faces of which terminate in inwardly directed cylindrical projections, and anti-friction bearings clamped between said cylindrical projections and interposed between said impeller and said cam portion. 5

17. In a spherical machine, a casing having a fluid-receiving chamber with spaced sides and spherical peripheral surfaces, said chamber being provided with a central shaft connection, an impeller member located obliquely across said chamber to form a plurality of reversely congruent semi-circular wedge-like actuating compartments, the outside portion of said impeller having a spherical surface located in close ad- 10 juxtaposition to the spherical surface of the chamber, a transverse separating means between said inlet and outlet ports received in a slot in said impeller, said shaft carrying a central 15 cam element cooperating with said impeller to hold it in relatively oblique position within said chamber and to cause its side walls and the sides of the chamber to move relatively over one another and the spherical outside surface of the 20 impeller to oscillate relatively laterally across said spherical peripheral surface, said impeller member consisting of two side annular plate members extending from said spherical peripheral surface to said central cam element, a central 25 cylindrical member extending between said plate members and extending circularly around said central cam element and peripheral spherical plate means extending between the periphery of 30 said side plate members. 35

18. In a spherical machine, a casing having a fluid-receiving chamber with spaced sides and spherical peripheral surfaces, said chamber being provided with inlet and outlet ports, and being provided with a central shaft connection, an impeller member located obliquely across said chamber to form a plurality of reversely congruent semi-circular wedge-like actuating compartments, the outside portion of said impeller having a spherical surface located in close ad- 40 juxtaposition to the spherical surface of the chamber, a transverse separating means between said inlet and outlet ports received in a slot in said impeller, said shaft carrying a central cam element 45 cooperating with said impeller to hold it in relatively oblique position within said chamber and to cause its side walls and the sides of the chamber to move relatively over one another and the spherical outside surface of the impeller to oscillate relatively laterally across 50 said spherical peripheral surface, said separating means consisting of a central fixed cone extending between and bearing upon the walls of said slot and said impeller and transverse wall members extending from the sides of said cone 55 to the spaced sides of said chamber. 60
